[57] CLAIM

The ornamental design for a vehicular seat or similar article, as shown and described.

DESCRIPTION

FIG. 1 is a front perspective view of a vehicular seat or similar article showing our new design.

FIG. 2 is a right side plan view thereof, the opposite side being substantially identical;

FIG. 3 is a front elevational view thereof;

FIG. 4 is a rear elevational view thereof;

FIG. 5 is a top plan view thereof; and,

FIG. 6 is a bottom plan view of the chair of the subject invention.
